UNITED STATES PATENT OFFICE.

JACQUES WOLF, OF BASEL, SWITZERLAND.

DEVICE FOR IMPRINTING PHOTOGRAPHIC PLATES, FILMS, AND THE LIKE.

Application filed June 11, 1926, Serial No. 115,331, and in Germany June 29, 1925.

This invention relates to a device for imprinting thin layers or films of chemical preparations supported on a carrier such as a glass plate, band and the like, and particularly to imprinting photographic plates, films and the like.

According to the invention the device operates in melting the thin layer or film on the carrier by the combined action of heat and pressure without injuring the carrier, and with this object the device comprises letter, numeral or the like elements which are arranged to be heated directly or by means of intermediate elements and means for applying same by slight pressure on the photographic plate or the like so as to imprint letters or numerals in the thin layer or film of chemical preparation on the plate by melting the layer. The characters may be imprinted one after the other or simultaneously so as to form words, numbers or the like.

The invention will now be described by way of example with reference to the accompanying drawing in which —

Figures 1 and 2 are longitudinal and cross sectional views respectively of a preferred constructional form of the invention, for use for example in connection with photography.

Figure 3 being a detail view showing the mounting of the type in the type disc.

Referring now to the drawing it will be seen that the letter or numeral elements *a* consist of type discs mounted in a vertically movable frame *b*, which bears, under the tension of a spring *c*, on a lever *d*. A stronger spring *f* tends to raise lever *d* which is arranged to be actuated by a hand lever *g* provided with a thumb *g'*. The type discs *a*, which may be adjusted rotationally as has previously been proposed by means of arms *h* arranged to engage separately with adjusting segments *i*, are provided with an electric heating device arranged axially therein.

A table *k* for supporting the photographic plate or the like to be operated on is disposed below the type discs, an apertured cover plate *m* subject to the tension of springs *n* being provided for holding the photographic plate on the table *k*.

When the handle *g* is depressed the thumb *g'* will exert a force on lever *d* in a direction opposite to that exerted by the spring *f*. Frame *b* is therefore released and the type

discs *a* mounted therein are pulled down under the tension of spring *c* on to a photographic plate or the like supported under the type discs. Thus numbers, words or the like are melted into the film on the photographic plate by the combined action of heat and pressure. When the handle *g* is released, spring *f* overcomes spring *c* so that lever *d* is raised together with the frame *b*, the cover plate *m* being simultaneously raised in order that the photographic plate can be withdrawn.

The type discs are preferably so constructed, or the types are so inserted in suitable carriers that the surfaces of the types to be printed are all in the same plane parallel to the table *k*, but the types are mounted in a spring controlled manner so as to be movable within limits in a radial direction, and, in the construction shown, (Figure 3), perpendicularly to the surface of the table *k* in order that any inequality in the distances of the surfaces of the types from the axis of the type discs is compensated for. The type the surface of which is at the greatest distance from the axis of the type disc is the first to come into contact with the photographic plate or the like, the remaining types being then permitted to be moved on by the lever *g* or spring *c* until all the types have come into contact with the photographic plate.

In the construction illustrated, an elastic yielding of the types is ensured by the fact that the locking balls *r* engaging into notches of the type discs when adjusting same are arranged together with their pressure springs *p* in the casing *l* in such a manner with respect to the table *k* that they operate radially to the type discs and in a direction perpendicular to said table *k*.

What I claim is:—

1. A device for imprinting photographic plates, films and the like, comprising adjustable type elements and means to cause them to act by combined action of heat and pressure upon the chemical preparation of said photographic plates, films and the like for imprinting purposes.

2. A device for imprinting photographic plates, films and the like, comprising a support for said plates, films and the like, adjustable type elements, means to heat the types of said elements and control means to produce a relative approaching movement between said type elements and said support

- for the purpose of imprinting by combined action of heat and pressure upon the chemical preparation of said photographic plates, films and the like.
3. A device for imprinting photographic plates, films and the like, comprising a support for said plates, films and the like, rotatably adjustable type discs, a common heating device for the types of said discs and control means to produce a relative approaching movement between said type discs and said support for the purpose of imprinting by combined action of heat and pressure upon the chemical preparation of said photographic plates, films and the like.
4. A device for imprinting photographic plates, films and the like, comprising a lower support for said plates, films and the like, separately adjustable type discs arranged above said support, a common central heating body located within said type discs and actuating means for lowering said type discs to produce imprinting by combined action of heat and pressure upon the chemical preparation of said photographic plates, films and the like.

In witness whereof I have hereunto signed my name this 1st day of June 1926.

JACQUES WOLF.
